(57) CLAIM

The ornamental design for a fashion jewelry eyeglass clasp, as shown and described.

DESCRIPTION

The article is a 2-piece necklace clasp serving equally as a decorative fashion jewelry piece. The article consists of a lower mount (to support eyeglasses) and an upper unit to which the eyeglass mount fastens.

FIG. 1 is a perspective view of a fashion jewelry eyeglass clasp showing my new design; and,

FIG. 2 is a front elevational view.
